UNITED STATES PATENT OFFICE

CHARLES C. ROTH, OF DENVER, COLORADO, ASSIGNOR TO THE DENVER TENT AND AWNING COMPANY, OF DENVER, COLORADO.

COMBINED SMOKE-FLUE AND VENTILATING DEVICE.

No. 809,223.

Specification of Letters Patent.

Patented Jan. 2, 1906.

Application filed December 27, 1904. Serial No. 238,548.

To all whom it may concern:

Be it known that I, CHARLES C. ROTH, a citizen of the United States, residing in the city and county of Denver and State of Colorado, have invented certain new and useful Improvements in a Combined Smoke-Flue and Ventilating Device; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to a combined smoke-flue and ventilating device, more especially adapted for use in tents or tent-cottages, but which may be advantageously employed in other structures.

20 The invention consists of a damper-controlled flue adapted to be mounted in the top of the structure and surrounded by a ventilating-flue which communicates at the top with the outer air and at the bottom with openings 25 adapted to be controlled by a rotary slide. In the construction shown in the drawings the device is applied to a tent or tent-cottage and the ventilating-flue is provided with openings which communicate with the space between 30 the roof proper and the fly.

Having briefly outlined my improved construction, as well as the function it is intended to perform, I will proceed to describe the same in detail, reference being made to the accompanying drawings, in which is illustrated an embodiment thereof.

In the drawings, Figure 1 is a fragmentary section taken through a structure equipped with my improved device. Fig. 2 is an underneath view of the device looking in the direction indicated by arrow 2 in Fig. 1.

The same reference characters indicate the same parts in both the views.

Let the numeral 5 designate a frame 45 rounding an opening in the top of the roof 6 of a tent or other structure. Above this frame 6 is a frame 7, surrounding an opening in the top of the fly 8 above the roof proper of the structure. Inserted in and secured to the 50 frames 5 and 7 is the ventilating device 9, preferably composed of metal and having its top provided with a covering 10, which is connected with the upper extremity of the ventilating device 9 by metal straps 12. The

top 10 is supported to leave a ventilating-space between it and the upper extremity of the part 9 for the escape of the air from the inside of the structure. In the bottom 9^a of the device 9 are formed a number of openings 13, controlled by a rotary slide 14, provided with a manipulating projection 15. The slide 14 is provided with openings 16, adapted to register with the openings 13 when the slide 14 is adjusted, to give the greatest possible ventilation. The ventilation, however, may be controlled at will, whereby the openings 13 may be left only partly exposed, or they may be entirely cut off, if desired.

Between the two frame parts 5 and 7 and communicating with the space 17 between the roof and the fly-openings 18 are formed on the device 9 for the escape of the air between the roof and the fly, thus preventing the accumulation of heated air within the said space. This is an important feature in structures with which this device will be used.

The rotary slide 14 is held in place by small clips 19, which overlap its exterior edge, while its interior edge is engaged by a flange 20, formed around a central opening formed in the bottom 9^a of the device 9. As shown in the drawings, this bottom 9^a is rectangular in shape and secured to the rectangular frame 5 by fastening devices 21.

Inserted in the opening in the bottom 9^a of the ventilating device 9 is a smoke-flue 22, which fits tightly in the said bottom and extends upwardly nearly to the top of the ventilating device. Above the bottom of the last-named device there is a considerable space 90 between the ventilating-flue and the smoke-flue. The upper part of the smoke-flue is provided with bow-shaped springs 23, which engage the inner surface of the ventilating device and properly center the smoke-flue there-in and at the same time lock the latter in position by reason of the frictional engagement between the ventilating device and the said springs. The smoke-flue projects below the bottom of the ventilating device, and its lower extremity may be provided with a detachable thimble 24, provided with a mesh covering 25, to prevent insects from entering the structure through the said flue. Above the thimble 24 is a slide 26, forming a damper which may be completely closed, if desired, when a stove is not employed. When a stove is used within the structure, the stove pipe or flue 27 may

be inserted in the lower extremity of the flue 22. In this event the thimble 24 is first removed. This thimble is only employed when the smoke-flue is not used in connection with 5 a stove. The damper 26 may be left open, if desired, even when a stove is not employed, since it increases the ventilating capacity of the device.

From the foregoing description the use and 10 operation of my improved device will be readily understood.

Having thus described my invention, what I claim is—

1. In a structure having a roof and fly, a 15 combined smoke-flue and ventilating device, consisting of a smoke-flue and a surrounding ventilating-flue, both flues being open-ended and forming independent passages between the atmosphere and the interior of the structure, and each flue being provided with suitable means for controlling said passage, the ventilating-flue also communicating with the space between the roof and fly.

2. The combination with a structure provided with a roof and fly, of a ventilating-flue mounted therein and passing through the roof and fly, the said flue communicating with the atmosphere at the top, the interior of the structure at the bottom, and with the space 30 between the roof and fly intermediate its extremities, and an open-ended, damper-controlled smoke-flue centrally located in the ventilating-flue, a suitable space being left between the two flues, substantially as described.

3. The combination of a structure having a 35 roof and fly respectively, provided with central openings, frames surrounding said openings, a ventilating-flue passing through the said openings and fastened to the frames, the flue having communication with the atmosphere at the top and with the interior of the structure at the bottom, and with the space between the roof and fly intermediate its extremities, a cut-off slide for controlling the bottom opening, and an open-ended flue centrally located in the ventilating-flue for the purpose set forth.

4. The combination with a structure having a roof and fly of a flue open at the top and bottom, a slide for controlling the bottom opening, the said flue communicating with the atmosphere at the top, the inside of the structure at the bottom and the space between the roof and fly intermediate its extremities another flue centrally located in the ventilating-flue, guides interposed between the two flues at the top for centering the central flue which is fitted tightly into the bottom of the ventilating-flue, the central flue being open-ended and having a mesh-covered thimble inserted 55 in its lower extremity.

In testimony whereof I affix my signature in presence of two witnesses.

CHARLES C. ROTH.
